TOY BOWLING GAME

John Kellinger, 439 49th St., Oakland, Calif.
Filed Mar. 23, 1961, Ser. No. 97,811
12 Claims. (Cl. 273—41)

The present invention relates in general to miniature bowling games and in particular is directed towards a game of this type wherein the bowling pins are suspended above the bowling surface.

In providing a toy bowling game it is of principal importance to simulate the features and playing characteristics of a conventional full size bowling alley. In a game wherein the pins are suspended rather than placed upon the bowling surface there is presented the problem of providing interaction between the various pins similar to that created by conventional pins falling and knocking one another down. Furthermore, it is necessary to adapt each pin so that proper impact thereon removes it from play in a manner analogous to a conventional bowling pin being knocked down. In addition it is desirable to provide a means for easily resetting the pins into playing position.

It is accordingly an object of this invention to provide a toy bowling game which closely simulates the pin interaction created by the pins on a conventional bowling alley.

It is another object of this invention to provide a means for suspending a bowling pin whereby sufficient force against the pin causes it to be moved upward into a position out of play from the other pins.

It is a further object of this invention to provide a means for suspending bowling pins whereby pins which have been removed from play can be easily reset into a playing position.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

FIGURE 1 is a top view of the instant bowling game.

FIGURE 2 is a side elevational view of the game illustrated in FIGURE 1, with portions broken away.

FIGURE 3 is a partial cross-sectional view of the bowling pin suspension mechanism of the instant invention.

FIGURE 4 is a cross-sectional view taken substantially in the plane indicated by line 4—4 of FIGURE 3.

With regard now to the invention in general, there are provided a plurality of bowling pins denoted by the numerals 11, 12, 13, 14, 15, 16, 17, 18, 19 and 20. Each of the bowling pins is suspended from a mounting plate 21 which is secured adjacent the upper edges of a pair of spaced apart vertical supporting walls 22 and 23. The bowling pins are oriented in a conventional array including a first row of pins 17, 18, 19 and 20, a second row of pins 14, 15, and 16, a third row of pins 12 and 13, and the head pin 11. In playing the game, the pins are suspended over a horizontal surface and a small ball such as a marble or the like is rolled towards the pins from in front of the head pin 11. When a pin is struck by the ball, or by the movement of another pin, it is removed into an uplifted position as typified by pins 11 and 16 in FIGURE 2. It is noted that the instant game is played according to the rules of conventional bowling which are sufficiently known in the art so as to merit no further discussion herein.

Referring now in detail to the means for suspending the bowling pins from the plate 21 there are provided ten

slots 24 in the plate 21, these slots being oriented in correspondence to the array of pins. Inasmuch as each of the ten pins are suspended in an identical manner, particular reference is made to FIGURES 3 and 4 wherein is shown one typical suspension mechanism 26 as provided by the instant invention. Mechanism 26 includes a lever arm 27 which is pivotally connected by means of a hinge 28 or the like to the upper surface of plate 21 adjacent the slot 24, the arm 27 being adapted to move from and towards the slot 24. A counter-weight 29 is mounted adjacent the upper end of lever arm 27. Now, as noted also in FIGURE 2, a connecting rod 31 is disposed through the slot 24 and is linked at its upper end to the lever arm 27, the lower end of rod 31 being adapted to have a bowling pin mounted thereon.

When a bowling pin is maintained in a downright position, i.e. with the rod 31 is disposed substantially vertically through the slot 24, the counter-weight 29 is disposed in essentially unstable equilibrium. A forward impact against the pin actuates the counter-weight 29 to move away from the slot 24 whereby the pin is withdrawn to an uplifted position.

It will be appreciated that as a practical matter it is not actually possible to maintain the counter-weight 29 in a true unstable equilibrium position. To solve this problem the counter-weight 29 is maintained in equilibrium with the lever arm 27 inclined slightly past the vertical towards the slot 24. As a means to restrict the lever arm from swinging all the way down towards the slot 24 a stop member 32 is rigidly secured to the lever arm 27. The stop member 32 is adapted to abut against the plate 21 when the lever arm 27 is in its inclined position thereby restricting the motion of the counter-weight 29 towards the slot 24. In this manner the invention effects for all practical purposes an unstable equilibrium disposition of the counter-weight 29.

For a more detailed description of the connection of rod 31 to the lever arm 27 reference is made to FIGURE 4. Preferably, a support arm 33 is rigidly fastened intermediate the ends of the lever arm 27 and is disposed over the slot 24 when the stop member 32 abuts against the plate 21. The connecting rod 31 is then swivelly secured adjacent its upper end to the support arm 33 whereby the bowling pin can swing in any direction about the arm 33. In addition, it is preferable that the arm 33 is bifurcated and includes separated portions 34 and 36 with a cylindrical rod 37 secured therebetween. A transverse hole 38 is then provided in the upper portion of the connecting rod 31 and the cylindrical rod 37 is disposed through the hole 38 to support the rod 31. It is seen that by making the hole 38 oversized the rod 31 is able to swing transversely as well as pivotally about the rod 37. The bowling pins are thus free to move to some extent in any direction thereby aiding the interaction between the various pins as is noted hereinafter.

In order to assist in removing the bowling pin to its uplifted position the invention preferably provides an element 39 which extends upwardly from the upper end of the connecting rod 31. The element 39 is disposed in confronting relation with the counter-weight 29 whereby a forward movement of the pin causes the element 39 to move backwards and strike the counter-weight 29. In this manner the counter-weight 29 is knocked backwardly into a stable equilibrium position and in so moving pulls the pin and rod 31 into a raised position.

As noted above, the connecting rod 31 is suspended in a manner whereby the bowling pin can move transversely as well as forwardly. It may, however, be desirable to limit the extent of transverse movement to prevent the pins from swinging to either side and interacting with other pins in an undesirable manner. It will be appreciated that only a small amount of transverse movement of

the rod 31 at its connection to rod 37 causes a significantly larger movement at the bottom of the pin. Consequently, attention is now directed to the stop member 32 which, as noted best in FIGURE 4, is provided with a bifurcated extension 41. The extension 41 is seen to comprise two separated portions 42 and 43 which extend around the connecting rod 31. It is preferable that the space between portions 42 and 43 be progressively increased at distances further from the lever arm 27. In this manner the allowable transverse movement of the bowling pin is increased in relation to the amount of forward pivotal movement of the pin.

With regard now to the novel means of providing proper interaction between the various pins, it is noted that ten contact plates 44 are each respectively secured adjacent the bottom of each of the ten bowling pins. Each contact plate 44 has a horizontal area substantially larger than the transverse cross-sectional area of a bowling pin. Consequently, it is unnecessary for a pin to swing extremely to the side in order to strike a pin in the next row, but instead the contact plate hits the pin. Preferably, the contact plates are constructed in a substantially triangular configuration, as is best seen in FIGURE 1. Each contact plate 44 is mounted adjacent one corner thereof to its corresponding bowling pin and is disposed with a leading edge 45 essentially parallel to the rows of pins. It is additionally preferred that the leading edge 46 have a convex arcuate shape in order to further improve the interaction between the pins. As regards the dimensions of the contact plates 44 it is preferred that the plate 44 mounted on the head pin 11 have a width less than the space between the pins 12 and 13. In this manner a ball which hits the head pin 11 from straight in front thereof will not make a "strike," i.e. remove all the pins, but instead simulates the "split" which would occur on a conventional bowling alley. The remaining contact plates 44 are preferably made with a width substantially equal to the distance between the centers of two adjoining pins in any row.

With regard now to the method and operation of playing the game, the invention is placed on a flat horizontal surface and a ball is rolled towards the pins from some distance in front of the head pin 11. In order to make a "strike" it is necessary to direct the ball to hit the head pin in addition to either the 12 or 13 pin. If, for example, the ball is rolled between the 11 and 13 pins and 11 pin is deflected slightly to the left and thus hits the 14 pin which in turn hits the 17 pin. Meanwhile, the ball also hits the 13 pin which strikes the 15 and 16 pins which in turn remove the 18, 19 and 20 pins. It will be appreciated that it is not possible to make a "strike" without hitting the head pin 11.

It is additionally noted that the various pins can be simply reset into playing position, after having been removed therefrom, by lifting upwardly a tab member 46 provided on the forward portion of the plate 21. In this manner the plate 21 is tilted so that the counter-weights all swing forward until the corresponding stop members each about against the plate 21. The plate 21 can then be returned to its normal horizontal position whereby the pins are all replaced in a downright position.

For increased structural support, a base plate 47 may be provided between the vertical walls 22 and 23 adjacent the lower edges thereof. In this embodiment it is of course necessary for the forward portion of the base plate 47 to be provided with a knife edge 48 in order that the ball be allowed to roll smoothly towards the pins.

What is claimed is:

1. In a bowling game, the combination comprising a mounting plate, means for supporting said plate above a flat horizontal surface, said plate having a slot therein, a lever arm pivotally connected at one end to the upper surface of said plate adjacent one end of said slot and movable from and towards said slot, a stop member rigidly connected to said lever arm and adapted to abut against

5 said plate when said lever arm is inclined from a vertical position towards said slot whereby said arm is restricted from moving towards said slot but is freely movable away therefrom, a counter-weight mounted adjacent the other end of said lever arm, a support arm rigidly connected intermediate the ends of said lever arm above said plate and disposed over said slot when said stop member abuts against said plate, a connecting rod swivelly connected to said support arm and extending downwardly through said slot, and a bowling pin mounted adjacent the lower end of said connecting rod.

2. In a bowling game, the combination comprising a flat mounting plate, means for supporting said plate above a flat horizontal surface, said plate having an elongated slot therein, a lever arm pivotally connected at its lower end to the upper surface of said plate adjacent one end of said slot, said lever arm adapted to move from and towards said slot, a counter-weight mounted adjacent the upper end of said lever arm, a stop member extending from the lower end of said arm towards said slot at an angle of less than 90 degrees with said arm whereby said stop member abuts against said plate when said arm is disposed past the vertical towards said slot thereby maintaining said counter-weight in a substantially unstable equilibrium position, a support arm rigidly connected intermediate the ends of said lever arm and disposed over said slot when said counter-weight is in said equilibrium position, a connecting rod swivelly secured adjacent its upper end to said support arm and extended downwardly through said slot, a bowling pin mounted adjacent the lower end of said connecting rod, and an element extending upwardly from the upper end of said connecting rod in confronting relation with said counter-weight.

3. A bowling game as described in claim 2 further characterized by a bifurcated member extending from said stop member around said connecting rod thereby restricting the transverse movement of said bowling pin.

4. A game as described in claim 3 further characterized by said bifurcated member having the space between the separated portions thereof progressively increased at further distances from the pivot connection of said lever arm.

5. In a toy bowling game, the combination comprising a flat mounting plate, means for supporting said plate above a flat horizontal surface, said plate having an elongated slot therein, a lever arm pivotally connected at its lower end to the upper surface of said plate adjacent one end of said slot, said lever arm adapted to move from and towards said slot, a counter-weight mounted adjacent the upper end of said lever arm, a bifurcated support arm rigidly connected intermediate the ends of said lever arm and disposed over said slot when said lever arm is in a substantially vertical position, a cylindrical rod connected transversely between the separated portions of said support arm and disposed in a substantially horizontal position, a connecting rod having a transverse cylindrical hole adjacent one end thereof pivotally connected to said support arm with said cylindrical rod disposed through said hole, said hole adapted to fit loosely around said cylindrical rod, said bifurcated support arm adapted to fit loosely about said connecting rod whereby said connecting rod can move transversely in addition to pivotally about said cylindrical rod, said connecting rod disposed downwardly through said slot, a bowling pin mounted adjacent the lower end of said connecting rod, an element extending upwardly from the upper end of said connecting rod in confronting relation with said counter-weight, and a bifurcated stop member rigidly connected to the lower end of said lever arm and extending around said connecting rod, said stop member adapted to abut against said plate when said lever arm is inclined towards said slot.

6. In a toy bowling game having ten bowling pins disposed in a conventional array of a first row of four pins, a second row of three pins, a third row of two pins and a

head pin, the combination comprising means for swivelly suspending each of said pins in an essentially unstable equilibrium position whereby impact against a particular pin in one direction causes that pin to move into an uplifted stable equilibrium position, and six contact plates each secured respectively adjacent the bottom of said head pin and each said pin in said second and third rows, each of said contact plates having a horizontally extending leading edge substantially wider than the transverse cross-sectional area of any said pin, said plate on said head pin adapted to engage the pins of said third row, said plates on said third row pins adapted to engage the pins of said second row, said plates on said second row pins adapted to engage the pins of said first row.

7. A bowling game as described in claim 6 further characterized by said contact plates each having a substantially triangular configuration, each said contact plate mounted adjacent one corner thereof to its respective pin and oriented in correspondence with the triangular array of bowling pins, said plates each having a leading edge spaced behind its respective pin and disposed in substantially parallel relationship with said rows, said plates of said second and third rows each having the width of its leading edge substantially equal to the distance between the centers of two adjoining pins in any row with the plates in each row being laterally spaced from each other, said head pin plate having the width of its leading edge less than the narrowest distance between the two pins in the third row.

8. A bowling game as described in claim 7 further defined by said leading edges each having a convex arcuate configuration.

9. In a toy bowling game having ten bowling pins disposed in a conventional array of a first row of four pins, a second row of three pins, a third row of two pins and a head pin, the combination comprising a mounting plate, means for supporting said plate above a flat horizontal surface, said plate having ten slots disposed therein in correspondence with said conventional array, ten lever arms each pivotally connected at one end to the upper surface of said plate adjacent one end of each corresponding slot, each said lever arm adapted to move pivotally from and towards each respective slot in a plane of pivotal movement oriented transversely to said rows, ten counter-weights each respectively mounted adjacent the remaining end of each said lever arm, means for restraining each said lever arm from moving towards said corresponding slots whereby each said counter-weight can be disposed in an equilibrium position with each said lever arm inclined from a vertical position towards each corresponding slot, ten support arms each respectively secured to said lever arms and disposed over said corresponding slots when said counter-weights are in said equilibrium position, and ten connecting rods each disposed respectively through one of said slots and each having its upper end swivelly secured respectively to said corresponding support arm, each of said bowling pins disposed below said plate and respectively mounted adjacent said connecting rods.

10. A toy bowling game as described in claim 9 further characterized by ten contact plates each secured respectively adjacent the bottom of each said bowling pin, each of said contact plates having a horizontal area sub-

stantially larger than the transverse cross-sectional area of any said pin.

11. In a bowling game having ten bowling pins disposed in a conventional array of a first row of four pins, a second row of three pins, a third row of two pins and a head pin, the combination comprising a pair of spaced apart vertical walls adapted for placement upon a flat horizontal surface, a flat mounting plate secured between said walls adjacent the upper edges thereof and disposed in a substantially horizontal position, said plate having ten slots therein disposed in correspondence with said conventional array, ten lever arms each pivotally connected at one end to the upper surface of said plate adjacent each corresponding slot, each said lever arm adapted to move pivotally from and towards each respective slot in a plane of pivotal movement oriented transversely to said rows, ten counter-weights each respectively mounted adjacent the remaining end of each said lever arm, ten stop members each extending respectively from the lower end of each said lever arm towards each corresponding slot at an angle of less than 90 degrees with each corresponding lever arm whereby each said stop member abuts against said plate when said lever arm is disposed past the vertical towards its corresponding slot thereby maintaining each said counter-weight in an essentially unstable equilibrium position, ten support arms each respectively rigidly connected intermediate the ends of each said lever arm and disposed over said corresponding slot when said corresponding counter-weight is in said equilibrium position, ten connecting rods each respectively swivelly secured adjacent one end to each support arm and each said connecting rod disposed downwardly through said corresponding slot, each said bowling pin respectively mounted adjacent the lower end of each said connecting rod, and ten elements each extending upwardly respectively from the upper end of each said connecting rod, each said element disposed in confronting relation with its corresponding counterweight.

12. In a bowling game, the combination comprising a mounting plate, means for supporting said plate above a playing surface, said plate having a slot therein, a counter-weight pivotally secured to the upper surface of said plate adjacent one end of said slot and movable from and towards said slot, stop means secured to said counterweight adapted to abut against said plate to maintain said counterweight in unstable equilibrium when it is in its position nearest said slot and adapted to allow said counterweight to pivot freely away from said slot to a position of stable equilibrium, a connecting rod swivelly secured to said counterweight at a position thereon spaced above the pivotal connection of said counterweight to said plate with said rod adapted to depend freely through said slot when said counterweight is in its position of unstable equilibrium, and a bowling pin mounted adjacent the lower end of the connecting rod.
